UNITED STATES PATENT OFFICE.

EBEN B. SANKEY, OF SALEM, MISSOURI.

COAT AND HAT RACK.

SPECIFICATION forming part of Letters Patent No. 595,253, dated December 7, 1897.

Application filed March 1, 1897. Serial No. 625,439. (No model.)

To all whom it may concern:

Be it known that I, EBEN B. SANKEY, a citizen of the United States, residing at Salem, in the county of Dent and State of Missouri, have invented certain new and useful Improvements in Coat and Hat Racks; and I do hereby declare the following to be a full, clear, and exact description of the invention, such as will enable others skilled in the art to 10 which it appertains to make and use the same.

My invention relates to certain new and useful improvements in hat and coat racks, the object being to provide a novel and effective form of device provided with locking 15 means whereby a hat and coat and also an umbrella hung thereon may be securely locked and thereby prevented from being stolen or removed by an unauthorized person.

To this end my invention consists, first, in 20 a coat and hat hanger comprising a top plate or body portion having a pivoted hook and clamping device to engage a hat and means for locking said parts so that the hat and coat cannot be removed by any other person than 25 the owner or a party possessing a key for unlocking said locking means.

My invention also consists in a novel construction of umbrella holder or clamp adapted to receive and hold an umbrella and connected 30 with the hat and coat locking mechanism in such manner that when the hat and coat are locked the umbrella will also be locked securely to prevent its removal.

My invention also consists in certain other 35 novel constructions, combinations, and arrangements of parts, as will be hereinafter more fully described, and specifically set forth in the appended claims.

In the accompanying drawings, Figure 1 is a 40 side elevational view of my improved device. Fig. 2 is a front elevational view of the same. Fig. 3 is a plan view of the rack. Fig. 4 is a side view of the locking-bar. Fig. 5 is a view of the two ends of the locking-chain, the parts being broken away for convenience of illustration. Fig. 6 is a side elevation of a modified form of hat and coat rack. Fig. 7 is an enlarged detail view showing the construction of the coat-hook thereof. Fig. 8 shows a front 45 view of the umbrella-clamping mechanism removed. Fig. 9 is a view of the clamp-actu-

ating rod of the umbrella-holder, and Fig. 10 is a cross-sectional view through the umbrella-holder on the line 10 10 of Fig. 8.

Referring to the drawings, the numeral 1 55 designates the body or back plate, having an enlarged horizontal base or bottom portion 2 and a vertical extension 3, provided at the top with a curved forwardly-extending clamping-flange 4, formed integrally therewith. 60 The said vertical extension 3 may be provided on its rear side with hooks 5, provided with openings 6, adapted to receive the lower end of a hanger-wire 7, the upper end of which is bent laterally outward at 7' and 65 formed into a hook or eye 8 at the end thereof, whereby the hat may be suspended, as hereinafter described.

The hat-clamping device comprises a hook 9, having a broad base 10 pivoted between 70 two ears 11 on the front of the vertical extension 3 and formed with a curved groove or slot 12 on the inner side of the said broad base, for a purpose hereinafter described. The outer end of this hook proper has a 75 curved surface 13, corresponding to the curvature of the said hat-clamping flange 4 in order that the crown and brim of the hat 14 when inserted between the same, as shown in Fig. 1, may be securely clamped without injury thereto. The hat, as above stated, is suspended upon the hooked end 8 of the hanger-wire 7, and this insures that the wall of the hat and brim thereof will be in position so as to be clamped between the clamp- 80 hook 9 and clamping-flange 4. A rigid coat-suspending hook 15 projects out from the broad base 2 of the rack and is adapted to receive a collar band or chain of the coat 85 in the usual manner. This coat-hook may 90 be and preferably is formed integrally with the said broad base 2.

The locking means for securing the coat to the said stationary hook and the hat to the pivoted clamping-hook comprises a flat locking bar or plate 17, provided with a curved or rounded upper end 18 and a vertical slot 19 at or about its center. This curved end of locking bar or plate is adapted to fit into and occupy the said curved groove or slot 12 100 in the broad base of the pivoted hat-clamping hook 9, and thereby prevent the same,

after it has been turned up, as shown in Fig. 1, to bear against the hat, from being pulled down again in order to disengage said hat, and thereby the hat is held securely clamped 5 between the curved upper edge of the hook and the curved flange 4 of the vertical extension 3. The chain 18' is suitably secured to the lower end of the said locking plate or bar, and is provided at its other end with a 10 rigid locking-plate 21, having a slot 22 formed therein. After the coat has been suspended from the rigid hook 15 the said chain is passed through the sleeves of the coat and the said locking-plate 21 is secured, as will now be de- 15 scribed. A lock-case 23 is positioned on the broad base 2 of the back part or the body of the rack and faces one side of the locking plate or bar 17, and a keeper 24 has position on the opposite side of the said locking-bar. The 20 lock-case is provided on the interior with a locking-plate 25 and locking mechanism of any preferred construction coacting therewith, the bolt of the said locking-plate being adapted to be thrown to project beyond the 25 end of the case and withdrawn from such position by means of a key inserted through the keyhole 26 in the top 27 of the said case. As before stated, any preferred construction of locking mechanism may be employed to 30 throw the bolt into and out of action; but it has not been deemed necessary to illustrate any special form of mechanism here, for the reason before stated. The chain having been passed through the sleeves of the coat, the 35 locking-plate 21, carried thereby, is placed alongside the slot 19 of the locking-bar 17 and the locking-bolt 25 is shot so as to enter the slots of the said locking bar and plate 21, so as to securely hold the same against dis- 40 engagement, and at the same time the pivoted hook is held clamped in engaged position with the hat by the upper end thereof. It will thus be seen that neither the hat nor the coat, while they are engaged, can be removed 45 from the rack unless the locking-plate 25 is thrown out of engagement with the locking-plate 21 and locking-bar 17, and thus any attempt to remove the hat or coat by an unauthorized person will be frustrated. 50 The umbrella-holder device comprises a base 28, adapted to be secured to the wall and provided with a vertical guideway 29 and a slot 30, opening through said base. A case 31 projects from the base and incloses two 55 pivoted clamping members 32 and 33. Each of these clamping members is provided with a broad body portion, through which a pivot-bolt 34 extends and pivots the clamp so that their jaws 25 have movement to and from each 60 other. The lower end of each clamp is formed with a slot 36, and said ends are adapted to have movement in the slot 30 of the base 29. A suspending-bar 35 projects from the horizontal base 2 of the hat and coat rack portion 65 and is provided with side flanges 36, forming

a grooved guideway 37 and cross-passages 38 through said flanges. An operating-bar 39 is constructed of a single piece of wire formed with a square elongated loop 40 at one end and a triangle or conical loop 41 at the other end 70 thereof. In practice this triangle or cone shaped end works in the guideway 29 and the two opposite sides thereof extend through the slotted ends 36 of the clamping members and are adapted to draw or spread the said two 75 ends closer together or farther apart to open or close the jaws thereof, as will be readily understood by reference to Fig. 10 of the drawings.

The elongated square loop 40 of the operating-rod is adapted to have its upper end seated in the cross slots or grooves 38, formed in the side flange-walls 36 of the suspending-bar 35.

In operation the triangle-shaped head or 85 loop of the operating-bar is actuated to cause the jaws to open and the umbrella is placed therein. The said triangular loop or head portion of the operating-bar is then operated to close the jaws and cause them to tightly 90 clamp the umbrella. The elongated square portion 40 of the operating-bar is then seated in the cross-notch 38, corresponding to the position of the jaws and size of the umbrella, and the lower end of the flat locking plate or 95 bar 17 of the coat and hat rack portion extends down the grooved guideway of the suspended bar 35 and holds the elongated square loop end of the operating-rod of the umbrella-clamp secured in the cross-walls 38, so that 100 the umbrella-clamping attachment cannot be removed. When this locking-plate is locked in the manner hereinbefore described, it will be seen that a hat, coat, and umbrella may be simultaneously locked to the rack. 105

In Fig. 7 a slightly-modified construction of the pivoted hat-clamping hook and coat-suspending hook, locking-bar, and locking device is shown. In this instance the lower broad base of the hat-clamping hook is not 110 provided with the curved groove or slot 12, as shown in the former figures, but has a rounded inner surface 43, and the rigid coat-suspending hook is provided with a T-shaped slot 44. In this construction the locking plate 115 or bar is provided with a staple 45, which takes the place of the slot 19, and the said bar is inserted through the said T-shaped slot in the coat-hook and lies parallel with and abuts against the front surface of the back plate or 120 body portion, and the upper end thereof, by taking between the said body portion and the curved or rounded surface 43 of the pivoted hat-clamping hook, prevents the latter from being turned down and thereby holds the hat-clamping hook in the same manner illustrated in the other form of rack. In this construction also a padlock 46 takes the place of the locking-plate 21, and the said padlock is adapted to engage with the said staple 45 and 130

hold the coat secure. The two forms of hat and coat rack, other than the changes described, are the same.

From the above description, taken in connection with the accompanying drawings, it will be seen that I have provided a simple and effective form of hat, coat, and umbrella rack which entirely prevents theft of the articles suspended thereon and which cannot be removed except by the owner or some authorized person carrying the key.

Having thus described my invention, what I claim as new, and desire to secure by Letters Patent, is—

15. 1. In a hat and coat rack, the combination with a back plate or body portion provided with a rigid clamping-flange at the upper end thereof, of a clamping member pivotally mounted on the body portion below said flange and adapted to be turned up so as to confine a portion of the hat between it and the said flange, a garment-suspending device carried by said body portion, a device to engage the garment, a locking-bar carrying said garment-engaging device and adapted to be interposed between the body portion and the base or inner end of the pivoted clamp, and means for locking the bar and garment-engaging device to maintain both in a locked position, substantially as described.

2. In garment-hooks, the combination with a body portion of a garment-suspending hook carried thereby, a removable locking-bar carrying a chain adapted to be passed through the sleeves of the garment, and a locking device adapted to engage the said locking-bar and the free end of the chain to hold the same in locked position, substantially as described.

3. In a hat and coat rack, the combination of a back plate or body portion provided with a rigid clamping - flange at the upper end thereof, a hat-clamping device pivoted at its lower end to said body portion and having the upper end adapted to bear against one side of the hat to hold the same clamped against the said clamping-flange, a coat-suspending hook below the said hat-clamp, a locking-bar adapted to engage the lower pivoted end of the hat-clamp to hold the same in clamped position and provided with a connection adapted to pass through the sleeves of the coat, said connection carrying a locking-plate at the free end thereof, and a locking device adapted to engage said locking-plate and locking-bar, substantially as described.

4. In a garment-rack, the combination with a back plate or body portion, of a garment-suspending hook projecting therefrom, a locking-bar provided at the lower end thereof with a chain adapted to be passed through the sleeves of the garment, said chain provided at its free end with a locking-plate, and a locking device to engage the said locking-bar and locking-plate and hold the same in locked position, substantially as described.

5. In a garment-rack, the combination of a

body portion having a projecting clamping-flange curved on the lower face thereof and hooks or eyes 5 on the back thereof, a hanger-wire having its lower end inserted in said hooks or eyes and provided with a forwardly-projecting upper extremity formed with suspending means, a pivoted clamping member having a clamping-face curved correspondingly to the said clamping-flange, and a locking device to hold the said clamping member in clamped position, substantially as described.

6. In a hat and coat rack, the combination with a hat-clamping device and a coat-suspending device, of a locking-bar adapted to engage said hat-clamping device and hold it in clamped position and provided with a chain adapted to be passed through the sleeves of the coat and a locking-plate, and a locking device adapted to engage the said locking-plate and locking-bar and hold the same in locked position, substantially as described.

7. In a hat and coat rack, the combination of a back plate or body portion having an enlarged base or horizontal portion, a rigid projecting clamping-flange, a hat-clamp pivoted thereto and provided with an outer clamping-face adapted in conjunction with the said flange to clamp the hat, a coat-suspending hook, a lock-inclosing case, a keeper on said body portion, and a locking-bar adapted to be passed between said locking-plate and keeper to engage with the pivoted hat-clamp to hold the same in a clamped position, a chain attached to the lower end of the said locking-bar and adapted to be passed through the sleeves of the garment and provided with a locking-plate, and locking mechanism in said locked case adapted to engage the said locking-bar and locking-plate, substantially as described.

8. In combination with a hat and coat rack provided with a locking-bar, an umbrella-holder comprising clamps to receive and hold the umbrella, an operating-rod to open and close said clamps, and a suspending-bar projecting from the hat and coat rack and adapted to receive and hold the said operating-rod, and coact with the said locking device of the hat and coat rack whereby the said operating-rod is held against movement in order that the jaws may be held closed about the umbrella, substantially as described.

9. In combination with a hat and coat rack provided with a locking-bar, an umbrella-holder comprising pivoted clamps to receive and hold the umbrella, an operating - rod adapted to open and close said clamps and adjustably connected with the rack, the said operating-rod being adapted to be held in locked position by the said locking-bar, substantially as described.

10. In combination with a hat and coat rack, provided with a locking-bar, and a suspending-bar provided with a series of notches, an umbrella - holder comprising two clamping members adapted to receive and hold the umbrella, said clamps being provided with

notched edges, and an operating-rod provided with a head or loop engaging said notched edges of the clamps and adapted to open and close the same and also with a loop adapted to be adjustably engaged with the said notched suspending-bar, and retained therein by the lower end of the said locking-bar, substantially as described.

In testimony whereof I have signed this specification in the presence of two subscribers.
